(57) CLAIM

The ornamental design of an over-the-door mirror with letterboard, as shown and described.

DESCRIPTION

FIG. 1 is a front elevation of the over-the-door mirror with letterboard.

FIG. 2 is a rear elevation of the over-the-door mirror with letterboard.

FIG. 3 is a right side elevation of the over-the-door mirror with letterboard.

FIG. 4 is a left side elevation of the over-the-door mirror with letterboard.

FIG. 5 is a top plan view of the over-the-door mirror with letterboard.

FIG. 6 is a bottom plan view of the over-the-door mirror with letterboard; and,

FIG. 7 is a perspective view of the over-the-door mirror with letterboard.

Portions of the over-the-door mirror with letterboard shown in broken lines form no part of the claimed design.
